UNITED STATES PATENT OFFICE.

DAVID McNAIR, OF BOSTON, MASSACHUSETTS, ASSIGNOR TO ROXBURY CARPET COMPANY, OF SAME PLACE.

DESIGN FOR CARPET.

Specification forming part of Design No. 11,088, dated March 25, 1879; application filed February 26, 1879.
[Term of patent 3½ years.]

To all whom it may concern:

Be it known that I, DAVID McNAIR, of Boston, in the county of Suffolk and State of Massachusetts, have invented a new and original Design for Carpets, of which the following is a specification:

The nature of my design is fully shown in the accompanying photographic illustration, in which—

a a a a represent figures of approximately hexagonal form, arranged in rows extending longitudinally of the piece, the figures of each row alternating with those of the adjoining rows. Each figure is decorated with a large bouquet, *b*. *c c c* represent borders extending diagonally across the piece, so as to form a kind of net-work, inclosing the figures *a* and defining one end of each figure. These borders *c* are ornamented at the points where they intersect by rosette-like figures *d*, and between the figures *d* with elongated hexagonal medallions or figures *e*, said figures *d e*

appearing to cover the borders *c c*. Ornamented spaces *f g h* occur between the figures *a* and the borders *c*.

I claim—

1. The design for a carpet, consisting of the ornamented figures *a* and the ornamented borders *c*, substantially as shown.
2. The design for a carpet, consisting of the borders *c c* and the ornamental figures *d e*, substantially as shown.
3. The design for a carpet, consisting of the ornamented figures *a*, ornamented borders *c*, and ornamented spaces *f g h*, substantially as shown.

In testimony whereof I have signed my name to this specification in the presence of two subscribing witnesses.

DAVID McNAIR.
